UNITED STATES PATENT OFFICE.

WILLIAM K. RANKIN, OF SCHENECTADY, NEW YORK, ASSIGNOR TO GENERAL ELECTRIC COMPANY, A CORPORATION OF NEW YORK.

ELECTRIC SWITCH.

Application filed November 14, 1922. Serial No. 600,804.

To all whom it may concern:

Be it known that I, WILLIAM K. RANKIN, a citizen of the United States, residing at Schenectady, in the county of Schenectady, 5 State of New York, have invented certain new and useful Improvements in Electric Switches, of which the following is a specification.

My invention relates to electric switches, 10 and especially to switches having contacts separable within a closed chamber which contains an insulating liquid.

In the operation of fluid break switches, 15 the arc drawn between the switch contacts upon their separation produces intense local heating of the insulating liquid ambient the arc path thereby vaporizing a part of this liquid and creating within the chamber a pressure which operates both to suppress the arc and to accelerate the separation of the contacts by its piston action on the movable contact.

One of the major objects of my invention 20 is to provide a switch of the above described type wherein a certain amount of liquid may be used repeatedly during circuit breaking operations, provision being made for the recovery of this liquid after each operation so that the same may be used again. To this end in the embodiment 25 of my invention herein disclosed, I provide a receptacle having a reservoir in its lower portion adapted to contain a small quantity of liquid which is one such as water that is not permanently affected by heat. Electrodes are provided which are separable beneath the surface of this liquid and the portion of the receptacle above the 30 sump is formed as a condensing chamber whereby the liquid vaporized by the arc is condensed after the arc has been extinguished and returned to the sump.

In order to facilitate its cooling and condensing action and to insulate the conducting portions thereof, I submerge the receptacle in an insulating liquid which also surrounds the main contacts of the switch.

Numerous other objects and advantages 45 of my invention will be in part obvious and in part explained in the following description taken in connection with the accompanying drawing in which Fig. 1 shows a vertical section of a single pole switch containing one embodiment of my invention,

some of the parts being cut away and others 55 shown in elevation. Fig. 2 is a sectional view of a modified form of receptacle or explosion chamber wherein additional strength is attained by imbedding rings of metal in the insulating material of which 60 the chamber is formed, care being taken to maintain a sufficient dielectric strength of insulation between contacts, and Fig. 3 is a view similar to Fig. 1, showing a modified form of switch for use on high power 65 circuits, where the intensity of the arc and the amount of vapor formed will cause a high pressure to be exerted against the walls of the explosion chamber, the construction of the chamber being such as to necessitate 70 a modified arrangement for the insulation of the contacts.

In Fig. 1 is shown a tank 10 adapted to contain an insulating liquid and in which rests an insulator 12 adapted to support a 75 contact 13 and an explosion chamber casing 14. The explosion chamber casing 14 is composed of insulating material, the inner surface of which is corrugated, thereby forming small annular condensing-chambers 80 15. The stationary electrode 16 is cup-shaped and forms the lower portion or sump of the explosion chamber.

The cover 20 of the tank 10 is constructed to permit the passage of the insulating operating rod 21 and also the insulating bushings 22 through which the switch leads 23 and 24 pass. The switch lead 24 is hollow in form and is fitted with a side connection and a stopcock 25 to which means may be attached to admit liquid 26 to the explosion chamber. The normal levels of the liquid in tank 10 and explosion chamber 14 are indicated by the shading. While various liquids may be used in the explosion chamber, I prefer to employ distilled water or in case the switch is used where the temperature falls below freezing, I may employ a mixture of water and glycerine.

The contact mechanism of the switch comprises primary and secondary contact members. The primary contact lever 30 is pivoted at 31 and supports a contact brush 32 adapted to cooperate with a stationary contact 13. The secondary contact lever 33 is pivoted at 34 and is connected to the operating rod 38 of the secondary contact 35 through a link 35 and pins 36 and 37. The

contact levers 30 and 33 are geared together and are operated by means of the insulating rod 21. The operating rod 38 enters the explosion chamber through a stuffing box provided in the aperture 40.

Provision is made for making the final break in the circuit at the movable electrode 38 by use of a sliding contact 45 which is in electrical connection with the stationary contact 16. The movement of this sliding contact 45 to follow the movable electrode 38 is caused by the pressure of the spring 46 which is compressed when the contacts close. The distance which the sliding contact 45 may move in the upward direction is limited by its head 50 striking against the under surface of the stationary contact 16. A cap 47 is provided to form a seat for the spring 46 and to make it unnecessary to seal the bearing of the sliding contact 45. Opening 51 is provided in the bottom of the stationary contact 16 for permitting free movement of the sliding contact 45.

An hydraulic dash pot 60 is attached to the chamber cover 41, the piston 61 of which is connected to the secondary contact lever 33 by the link 62. An aperture 55 in the dash pot body is designed to permit free movement of the piston 61 during the first part of its downward stroke. As the piston 61 passes below the aperture 55 near the end of the stroke, the dash pot serves as a cushion and the contact lever is brought to rest without shock.

Low resistance connection is maintained between the chamber cover 41 and the contact member 30 and lever 33 by the use of flexible leads 65.

Where it is desired to use an explosion chamber adapted to withstand high internal pressure, I can provide reinforcing means for the insulated explosion chamber. One such means is shown in Fig. 2 wherein 52 represents an inner insulating condensing casing and 53 an outer shell formed of insulation and reinforced by interlocked annular metallic members 54.

In Fig. 3 I have shown another arrangement by which the explosion chamber may be made to withstand high internal pressure. In this form of my invention the metal casing 114 is a modified form of the casing shown in Fig. 2 and is adapted to receive a removable condensing lining 115 which is a modified form of that shown in Fig. 2. The explosion chamber casing is supported from the tank 10 by an insulator 111 and is held, by a clamping member 150, in a position permitting removal of the explosion chamber. An example of such a fastening means is shown in the patent to Ball, 945,671, Jan. 4, 1910. The primary contact plate 113 is in electrical contact with the explosion chamber casing 114. The ex-

plosion chamber casing is provided with a metallic cover 141 to which the hollow lead 24 is fastened. A lead 23 is connected to the contact mechanism support 142 which is supported from the cover 141 by the insulator 143 and the insulating bushing 144. Gas tight connections are provided between the insulating bushing 144 and the explosion chamber 115. The stuffing box 148 is provided for the purpose of preventing the escape of gas through the opening provided for the movable contact 38.

In operating under load from the closed position of the switches shown in Figs. 1 and 3, the operating rod is raised by operating means external to the switch. The operating means is not shown but may be of any well known construction such, for example, as that shown in patent to Hewlett and Button 973,657, Oct. 23, 1910. Movement of the primary brush 32 away from its contact will cause all the current to flow through the auxiliary electrode 38. The insulating liquid 11 will extinguish any arc which may tend to form between the brush 32 and its cooperating contact and introduce a high resistance to the passage of current between brush and contact.

After the separation of the primary contacts the electrodes 38 and 45 are separated beneath the surface of the liquid 26. This results in the rapid vaporization of the liquid which greatly increases the pressure within the explosion chamber. This pressure assists in forcing the electrode 38 through the opening 40 thus producing a rapid separation of the contacts. Any arc or incipient arc which may be formed at the separation of these electrodes is quickly extinguished and the circuit broken. The action of water in extinguishing the arc is in many respects similar to that described in the patent to Nicholson 1,402,316, Jan. 3, 1922.

The hot vapors impinging against the sides of the relatively cold walls of the chamber 15 will be condensed and the liquid so formed will flow to the sump, thus being available for further operation of the switch.

The dash pot 60 is provided with an opening 55 designed to permit free movement of the piston 61 and the associated secondary contact lever 33 during the first part of the opening movement of the switch. As the piston 61 passes the opening 55 in its downward movement, however, the oil beneath the piston is compressed and forced out through a small opening in the bottom of the dash pot thus serving to cushion the piston and bring the electrode 38 to rest without shock. In the closing operation of the switch, the opening 55 functions to permit rapid acceleration of the secondary contact 38 during the latter part of its closing

movement, the shock incident to closure of the switch being absorbed by the spring 46 which supports the movable contact 45.

In closing the switch the operations are reversed. The operating rod is raised to cause movement to close both the primary brush 32 and the movable electrode 38. In so doing the movable electrode 38 contacts with the sliding contact 45 and establishes the circuit before the primary brush makes contact. Between the time that the movable electrode 38 has made contact with the sliding contact 45 and the instant of final closing at the primary contact brush 32, both the movable electrode 38 and the sliding contact 45 move downwardly, contact between the two being maintained by the spring 46.

Switches of the class described may be used for a large variety of conditions of service and my invention in its broader aspects is not limited to the particular constructions shown herein. While I have shown the contact levers 30 and 33 as connected together by means of intermeshing gears, it is apparent that other suitable means may be employed for securing the desired mechanical movement. Other changes apparent to those skilled in the art may be made without departing from the scope of my invention.

What I claim as new and desire to secure by Letters Patent of the United States, is,—

1. In a switch, a sealed explosion chamber comprising a reservoir in its lower portion and a condensing chamber in its upper portion.

2. A switch of the type wherein a circuit is broken by the separation of contacts in proximity to a liquid which is vaporized but not permanently affected thereby, characterized by the fact that means are provided for condensing the vapor of said liquid.

3. A switch of the type wherein a circuit is broken by the separation of contacts beneath the surface of a liquid which is vaporized but not permanently affected thereby, characterized by the fact that means are provided for condensing the vapor of said liquid.

4. A switch of the type wherein a circuit is broken by the separation of contacts in a reservoir containing a liquid which is vaporized but not permanently affected thereby, characterized by the fact that means are provided for the condensation of the vapor of said liquid and for the return of the condensed liquid to said reservoir.

5. In a switch having an explosion chamber formed with a metallic reservoir in its lower portion, an electrode in said reservoir and electrically connected thereto, a metallic cover for said explosion chamber, means connecting said cover and reservoir and serv-

ing to insulate them from one another, an electrode passing through said cover and electrically connected thereto and terminals connected to said reservoir and cover.

6. In a switch having an explosion chamber formed of conducting portions and an intermediate insulating portion, separable electrodes connected to said conducting portions, one of said electrodes being formed with a passage for the supply of liquid to said chamber.

7. The combination of a sealed container, contacts separable within said container but not completely withdrawable therefrom, said contacts being separable in a liquid which is vaporized but not permanently affected by the breaking of a circuit by said contacts, a tank surrounding said container, said tank being adapted to contain an insulating liquid within which said container is immersed.

8. The combination of a sealed container, secondary electrodes having contact surfaces separable in said container to break a circuit whereby an arc formed by the separation of said contacts creates pressure within said container, said surfaces remaining at all times within said container, a tank enclosing said container, said tank being adapted to hold a liquid within which said container is immersed, and primary electrodes for carrying the main load current separable in said liquid.

9. A switch comprising a sealed chamber containing a liquid, secondary contact members separable within said liquid, said liquid being vaporized but not permanently affected by the breaking of a circuit by said contact members, a tank enclosing said container, said tank being adapted to hold a liquid within which said container is immersed, and primary contact members mounted outside said chamber and separable within said tank.

10. A switch having a sealed explosion chamber adapted to contain an arc extinguishing fluid, electrodes separable within said chamber to break a circuit whereby an arc formed by the separation of said electrodes creates pressure within said chamber, and a terminal connected to one of said electrodes through the wall of said chamber, said terminal being formed with a passage for the supply of fluid to said chamber.

11. A switch comprising a sealed chamber containing water, primary contact members for carrying the main load current separable without said chamber, and secondary contacts within said chamber for breaking the circuit whereby an arc formed at said secondary contacts vaporizes said water and creates pressure to extinguish said arc and to accelerate the separation of said contacts.

12. A switch comprising a sealed chamber immersed in a cooling and insulating

liquid, and having a reservoir at its bottom adapted to contain an arc extinguishing liquid, contacts separable within said chamber to break a circuit arranged so that any arc formed will vaporize said arc extinguishing liquid and create pressure within said chamber to suppress said arc, the inner surfaces of said chamber acting to condense the vapor produced and return the same to said reservoir.

13. A switch comprising a sealed chamber provided with a corrugated wall to form a cooling surface and having a reservoir at its bottom adapted to contain an arc extinguishing liquid, contacts separable within said chamber to break a circuit arranged so that an arc formed will vaporize said liquid and create pressure within said chamber to suppress said arc, said cooling surface acting to condense the vapors produced and return the same to said reservoir.

14. An electric switch of the type wherein a circuit is broken by means of contacts arranged upon the separation thereof to extinguish any arc which may be formed by drawing the same beneath an arc extinguishing liquid, comprising in combination a sealed chamber having a reduced portion at the bottom thereof forming a reservoir adapted to contain said arc extinguishing

liquid, means for operating one of said contacts extending through a wall of said chamber whereby upon the separation of said contacts, vapors produced by the interruption of the circuit will accelerate the separation of said contacts and be condensed on the walls of said chamber and returned to said reservoir.

15. An electric switch comprising a sealed chamber provided with a corrugated wall 40 and containing water in the lower portion thereof, contacts arranged in the lower portion of said chamber whereby any arc formed upon the separation of said contacts will be drawn in said liquid, means for 45 operating one of said contacts extending through a wall of said chamber whereby upon the interruption of the circuit by the separation of said contacts the vapor pressure produced in said sealed chamber will 50 assist in extinguishing the arc and accelerate the separation of said contacts, said vapors being condensed by the cooling action of said corrugated wall and returned to the lower portion of the chamber. 55

In witness whereof I have hereunto set my hand this eleventh day of November, 1922.

WILLIAM K. RANKIN.
